US00D829286S

(12) United States Design Patent (10) Patent No.: US D829,286 S
(45) Date of Patent: * Sep. 25, 2018

(54) EXERCISING APPARATUS

(71) Applicant: Woochang Bae, Eastwood (AU)

(72) Inventor: Woochang Bae, Eastwood (AU)

() Term: 15 Years

(21) Appl. No.: 35/502,915

(22) Filed: Apr. 18, 2017

(80) Hague Agreement Data

Int. Filing Date: Apr. 18, 2017

Int. Reg. No.: DM/095780

Int. Reg. Date: Apr. 18, 2017

Int. Reg. Pub. Date: May 5, 2017
